* cited by examiner

Primary Examiner — Dominic Simone(74) *Attorney, Agent, or Firm* — David A. Burge(57) **CLAIM**

I claim the ornamental design for a pyramidal-shaped package enclosing a pyramidal-shaped leveling device, as shown and described.

DESCRIPTION

FIG. 1 is a perspective view of my new design showing principally front and left side features thereof;

FIG. 2 is a tilted front view as seen from a plane indicated by a line 2-2 in FIG. 1;

FIG. 3 is a front view thereof;

FIG. 4 is a rear view thereof;

FIG. 5 is a top view thereof;

FIG. 6 is a bottom view thereof; and,

FIG. 7 is a right side view thereof, it being understood that a left side view would be a mirror image.

The transparent, pyramidal-shaped package portion of the design has four equilateral triangular surfaces of identical size. A pyramidal-shaped leveling device is enclosed in the transparent package portion of the design and includes four transparent balls of identical size that are connected by six transparent arms of equal length and uniform exterior diameter.
